CLAIM

The ornamental design for an illumination housing for an operating room microscope, substantially as shown and described.

DESCRIPTION

FIG. 1 is a perspective view of an illumination housing for an operating room microscope showing our new design;

FIG. 2 is a front elevational view thereof;

FIG. 3 is a rear elevational view thereof;

FIG. 4 is a left side elevational view thereof, the right side being a mirror image;

FIG. 5 is a top plan view thereof;

FIG. 6 is a bottom plan view thereof;

FIG. 7 is a greatly reduced left side elevational view thereof with an operating room microscope shown in in broken lines for illustrative purposes only.

FIG. 1

FIG. 2

FIG. 3

FIG. 4

FIG. 5

FIG. 6

FIG. 7
